United States Patent Office

Des. 193,253
Patented July 17, 1962

193,253

BOX

George R. Stehl, New York, N.Y., and Francis E. Blod,
New Canaan, Conn., assignors to Domus Products
Inc., New York, N.Y., a corporation of New York

Filed Sept. 28, 1960, Ser. No. 62,300

Term of patent 14 years

(Cl. D58—12.6)

FIG. 1.

FIG. 2.

FIG. 3.

FIG. 4.

FIG. 5.

FIG. 1 is a top plan view of a box embodying our new design;

FIG. 2 is a front elevational view thereof;

FIG. 3 is a side elevational view thereof;

FIG. 4 is a rear elevational view thereof; and

FIG. 5 is a perspective view thereof, showing the lid partially open.

We claim:

The ornamental design for a box, substantially as shown.
